UNITED STATES PATENT OFFICE.

GEORGE P. ROBERTS, OF ST. LOUIS, MISSOURI.

IMPROVED BOX-MACHINE.

Specification forming part of Letters Patent No. 37,827, dated March 3, 1863.

To all whom it may concern:

Be it known that I, GEO. P. ROBERTS, of the city and county of St. Louis, and State of Missouri, have invented a new and useful device for holding the parts of boxes while the same are being nailed together, which invention I denominate "Box-Machine;" and I do hereby declare that the following is a full, clear, and exact description thereof, reference being had to the accompanying drawings, and to the letters of reference marked thereon, and made to form a part of this specification.

In the manufacture of boxes, especially the smaller classes, much difficulty has been experienced in the proper holding of the parts to be nailed or screwed together, thereby involving a great deal of time, labor, and care.

The object of my invention is the construction of a machine, which may be simple, cheap, and practical, by means of which the parts of boxes may be properly secured and held during the process of nailing, and which at the same time may answer as a gage in the construction of boxes, thereby effecting the saving of much time, labor, and expense, and facilitating the proper and perfect finish to boxes.

The nature of this invention relates to the employment of adjustable stocks and spring-clamps, by means of which the parts of boxes to be nailed may be held, as hereinafter described, specified, and represented.

In reference to the accompanying drawings, Figure 1 is a perspective view showing the front of my improved box-machine, and Fig. 2 is a perspective view showing the rear of the same. Fig. 3 is a top view of the spring-clamp.

A represents the frame of the machine, which may be formed of wood or metal in a strong and substantial manner, and of a size adapted to the class of boxes intended to be made.

B is a gage-plate rigidly and permanently secured to the frame A with its front face at a perfect right angle with the face A' of the frame A.

C represents the adjustable gage-stocks, arranged with their faces at perfect right angles with the face A' of frame A, and also with the front face of plate B. These stocks are adjustable laterally in such manner as to be

adapted to the length of the box to be constructed by means of the thumb-screws d and slots f.

g represents the clamps, which are rigidly secured to rods h, distinctly shown in Fig. 3, and formed to extend forward and fit into recesses in stocks C. (Shown in Fig. 2.) The clamp-rods h are arranged in suitable bearings, i i', the bearings or blocks i being adapted to act as stops for the spring j. The outer ends of the rods h are formed with screw-threads, as shown clearly in Fig. 3, and are adapted to fit the female screw-caps k. The inner ends of said rods h are provided with caps l, which are formed with a cavity adapted to receive the cords m, the said cords m being arranged to pass over pulleys n through the face A' to the under side of lever p, where they may be secured upon a suitable pin in such manner as to be tightened or loosened at pleasure. The foot-lever p is pivoted to the base A'' of the frame, and provided with a spring, r, which holds it up and prevents it from acting upon the clamp-rods h through the medium of the cords m, except when depressed.

S is a cup, which may be used for the holding of nails. The clamp-rods h, together with the working parts of the machine in rear of the plate B, may be covered, and thereby kept clean and free from dust. The tension of the springs may be regulated by turning the screw-caps k.

The operation of my invention may be described as follows: The stocks C being adjusted by means of the thumb-screws d to the length of the box to be made, the operator will depress the lever p with his foot, thereby drawing the clamps g inwardly toward each other through the medium of cords m and rods h until sufficient space is afforded between the said clamps g, and the faces of the stocks to receive the end pieces, as t of the box. The lever p will then be released, and the said end pieces held firmly against the stocks C by the clamps g, through the medium of springs j and rods h, in proper position to receive one of the side pieces of the box. The said side piece will then be placed between the stocks C, and pressed firmly against the plate B, and upon the end pieces, t, which necessarily brings it to a perfect fit upon the said end pieces and into the proper position to be nailed. The next

two side pieces will be nailed in the same manner; then if it is desired to nail the fourth side piece or top to the box, the end pieces will be released from the clamps *g*, so that said clamps may be allowed to retreat into the recesses in the stocks *C*; then the unfinished box may be inserted between the stocks and the last side piece or top of the box nailed on, as before described.

From the foregoing description it will be readily seen that the plate *B* and the stocks *C* are made to act as a perfect gage in the construction of boxes, thereby relieving the operator of all care in fitting the pieces of boxes together, the material for the boxes being always properly prepared before the operation of nailing.

Having thus described my invention, what

I claim as new, and desire to secure by Letters Patent, is—

1. The employment of the adjustable gage-stocks *C*, in combination with the plate *B*, all being constructed and arranged to operate substantially as and for the purposes set forth.

2. The spring-clamps *g*, constructed and arranged to operate substantially as herein described, in combination with the stocks *C*, as and for the purposes set forth.

In testimon of which invention I have hereunto set my hand and seal this 20th day of December, 1862.

GEO. P. ROBERTS. [L. S.]

In presence of—
H. E. CLIFTON,
E. A. SKULE.
